UNITED STATES PATENT OFFICE.

ALBERT W. KELIN, OF PITTSBURGH, PENNSYLVANIA.

STOPPER-EXTRACTOR.

1,260,394.

Specification of Letters Patent. Patented Mar. 26, 1918.

Application filed November 14, 1917. Serial No. 201,999.

To all whom it may concern:

Be it known that I, ALBERT W. KELIN, a citizen of the United States, residing at N. S. Pittsburgh, in the county of Allegheny and State of Pennsylvania, have invented certain new and useful Improvements in Stopper-Extractors, of which the following is a specification, reference being had to the accompanying drawings.

This invention relates to certain improvements in stopper extractors and has relation more particularly to a device of this general character especially designed and adapted for use in connection with fiber disks employed with milk bottles or the like, and it is an object of the invention to provide a novel and improved extractor which may be readily and conveniently engaged with the disk and which also serves to facilitate the removal or application of the disk until the bottle or the like is emptied of its contents.

Another object of the invention is to provide a novel and improved device of this general character which includes a head adapted to pierce the disk together with means co-acting with said head to clamp the disk after the same has been pierced and which also serves to close the opening affected by the piercing of the disk so that vitiated air or foreign substances are prevented from entering within the bottle in the event the disk should be again applied after being once removed.

The invention consists in the details of construction and in the combination and arrangement of the several parts of my improved stopper extractor wherein certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood I will now proceed to describe the same with reference to the accompanying drawings wherein:

Figure 1 is a view partly in section and partly in elevation of a stopper extractor constructed in accordance with an embodiment of my invention, a co-acting cap being indicated by dotted lines; and

Fig. 2 is a sectional view taken substantially on the line 2—2 of Fig. 1 and in the direction of the arrow.

As disclosed in the accompanying drawings 1 denotes a head or knob of predetermined configuration and dimension and provided in its inner face with the recess or socket 2. 3 denotes an elongated shank extending within the socket 2 at substantially the longitudinal center thereof and provided with a threaded extremity engageable within the handle or knob 1 whereby said shank 3 and knob 1 are arranged in assembled relation. The shank 3 is of a length to extend beyond the open end of the recess or socket 2 and the outer end of said shank is provided with a spear head 4 adapted to be forced through a bottle cap of a type generally employed for sealing milk bottles or the like.

The shank 3 is loosely disposed through the axial center of a clamping and sealing plate 5 and said plate 5 is constantly urged toward the head 4 through the medium of the expandible member 6. As herein embodied the expandible member 6 consists of a spiral spring encircling the shank 3 and interposed between the plate 5 and the base or bottom of the recess or socket 2.

After the head 4 has been forced through a cap the shank is given a quarter turn so that the head cannot be withdrawn through the opening produced in the cap. The expandible member 6 serves to cause the plate 5 to clamp the disk between the plate and the inner end portion of the head 4. The plate 5 is of a diameter in excess of the major diameter of the head 4 and therefore engages the cap in such a manner as to prevent vitiated air or foreign substances to pass through the opening produced in the cap by the head 4 and which is of particular advantage when the cap has been used to seal the bottle after the cap has been once removed.

My improved extractor is adapted to be maintained in engagement with the cap until after the bottle or the like with which the cap co-acts has been completely emptied of its contents and by having the plate 5 substantially seal the opening produced in the cap by the head 4 it will be at once understood that the contents of the bottle or the like, particularly when in a refrigerator

or similar place of storage will not become tainted by vitiated air or by foreign substances.

From the foregoing description, it is thought to be obvious that a stopper extractor constructed in accordance with my invention is particularly well adapted for use by reason of the convenience and facility with which it may be assembled and operated and it will also be obvious that my invention is susceptible of some change and modification without materially departing from the principles and spirit thereof, and for this reason I do not wish to be understood as limiting myself to the precise arrangement and formation of the several parts herein shown in carrying out my invention in practice except as hereinafter claimed.

20 I claim:

A device of the character described comprising a knob provided with a socket in

one of its faces, a shank secured to the knob and extending through the socket at substantially the center thereof, said shank extending beyond the open face of the socket, the outer end of the shank being provided with a spear head, a clamping plate loosely mounted upon the shank inwardly of the head, and a coil spring encircling the shank 30 and interposed between the plate and the bottom of the socket and constantly urging the plate toward the head, said plate being of a diameter in excess of the major diameter of the head to seal the opening in the 35 cap resulting from the passage of the head through the cap.

In testimony whereof I hereunto affix my signature in the presence of two witnesses.

ALBERT W. KELIN.

Witnesses:

STEWART R. ABBOTT,
LEONARD C. WALLSER.
